UNITED STATES PATENT OFFICE.

ISAAC SMIGEL, OF EAST ORANGE, NEW JERSEY.

DESK-PAD.

No. 811,334.

Specification of Letters Patent.

Patented Jan. 30, 1906.

Application filed September 30, 1905. Serial No. 280,758.

To all whom it may concern:

Be it known that I, ISAAC SMIGEL, a citizen of the United States, residing in East Orange, county of Essex, State of New Jersey, have 5 invented certain new and useful Improvements in Desk-Pads, of which the following is a specification, reference being had therein to the accompanying drawings, in which—

Figure 1 is a plan view of the pad; Fig. 2, a 10 sectional view on the line 2 2 of Fig. 1, and Fig. 3 a sectional view on the line 3 3 of Fig. 1.

The object of the invention is to provide a pad in the usual form and having corner-pockets to receive the corners of a blotter.

15 In addition to these main corner-pockets the pad is provided with supplemental pockets formed in the top pieces of the main pockets, these supplemental pockets being adapted to receive calendar-pads or memorandum pads 20 or cards or cards bearing any desired memorandum. These supplemental pockets are also designed to receive blank cards or slips of paper on which any desired memorandum may be written or pictures or photographs.

25 Referring to the various parts by numerals, 1 designates the pad proper; 2, the main pockets, which are adapted to receive the corners of the desk-blotters. Formed in the corner-pieces which constitute the top of the 30 corner-pockets 2 are supplemental pockets 3, these supplemental pockets being provided with bottom pieces 4. The opening into these supplemental pockets is at the inner edge of the main pockets, as shown clearly in 35 Figs. 2 and 3. In the top of the main pockets openings 5 are formed, through which the contents of the supplemental pockets may be viewed. Into these supplemental pockets cards 6 may be inserted, as shown clearly in

40 Figs. 2 and 3, said cards being readily removable through the opening into said pocket at the inner edge of the top piece of the main pocket. I prefer to print on some of these cards calendars, as shown in the lower left-hand corner of Fig. 1, said cards being readily changed at the end of each month. I also intend to use these pockets for the reception of pictures, said pictures being viewed through the openings 5, as shown in the upper left-hand corner of Fig. 1. It will be readily seen 45 that these supplemental pockets may be used for a great variety of purposes and that the

main pockets may be used as independent holders for memorandum-slips and for the reception of the corners of the blotter.

55

I wish it understood that I do not desire to limit myself to any specific form of supplemental pocket or to any specific construction thereof, as said pocket may be made in any desired manner and of any desired form or shape. I also desire it understood that the shape of the opening through the top piece of the main pocket may be of any desired shape or size, the elliptical form being shown merely by way of illustration and not with a view of 60 limiting the invention to that shape of opening.

Having thus described my invention, what I claim is—

1. A desk-pad provided with main corner-pockets adapted to receive the corners of a blotter, the top pieces of said corner-pockets being formed with supplemental pockets, open at the inner edges of said main pockets, openings being formed through the tops of 75 said main pockets into the supplemental pockets, whereby the contents of the supplemental pockets may be viewed through the openings in the tops of the main pockets.

2. A desk-pad provided with main corner-pockets formed with top pieces, and supplemental pockets formed in said top pieces.

3. A desk-pad provided with main corner-pockets formed with top pieces and supplemental pockets formed in said top pieces, the 85 entrance to said supplemental pockets being at the inner edges of said top pieces, said top pieces being formed with openings through which the contents of the supplemental pockets may be viewed.

4. A desk-pad provided with main pockets at its corners, the top piece of one of said pockets being provided with a supplemental pocket, an opening being formed in said main pocket through which the contents of 95 said supplemental pocket may be viewed.

In testimony whereof I hereunto affix my signature, in the presence of two witnesses, this 29th day of September, 1905.

ISAAC SMIGEL.
